United States Patent

Des. 234,749
Patented Apr. 8, 1975

234,749

PACKAGING CONTAINER FOR GLASSWARE OR THE LIKE

Hamilton M. Ross, Toledo, and John A. Tuttle, Perrysburg, Ohio, assignors to Owens-Illinois, Inc., Toledo, Ohio

Filed Sept. 25, 1972, Ser. No. 292,087

Term of patent 14 years

Int. Cl. D9—03

U.S. Cl. D9—184

FIG. 1

FIG. 2

FIG. 1 is a top perspective view of a packaging container for glassware and the like showing our new design; and

FIG. 2 is a bottom plan view thereof.

The sides opposite those seen in FIG. 1 are substantially the same in appearance as the sides shown.

We claim:

The ornamental design for a packaging container for glassware or the like, substantially as shown and described.
